UNITED STATES PATENT OFFICE.

LEONID ALANCHIKOFF, OF PHILADELPHIA, PENNSYLVANIA.

COMBINATION-PADLOCK.

1,147,133.

Specification of Letters Patent. Patented July 20, 1915.

Application filed January 20, 1915. Serial No. 3,284.

To all whom it may concern:

Be it known that I, LEONID ALANCHIKOFF, a citizen of the United States, residing at Philadelphia, in the county of Philadelphia and State of Pennsylvania, have invented certain new and useful Improvements in Combination-Padlocks, of which the following is a specification.

My invention relates to improvements in combination padlocks, the object of the invention being to provide an improved arrangement of pivoted tumblers controlled by an improved arrangement of rotary and longitudinally movable plungers for operating a spring-pressed bolt to release the shackle and allow the latter to be thrown open by its spring.

A further object is to improve upon the construction set forth in Patent No. 1,123,061 granted to me December 29th, 1914, on an improved padlock.

With these and other objects in view, the invention consists in certain novel features of construction and combinations and arrangements of parts as will be more fully hereinafter described and pointed out in the claims.

In the accompanying drawings: Figure 1 is a view in elevation with the casing front removed showing the parts in normal locked position. Fig. 2 is a similar view illustrating the first step in the unlocking operation. Fig. 3 is a similar view illustrating the second step in the unlocking operation. Fig. 4 is a similar view illustrating the third step which completes the unlocking operation. Fig. 5 is a view on an enlarged scale illustrating my improved arrangement of tumblers showing in dotted lines the conformation of the respective tumblers. Fig. 6 is a view in transverse section on the line 6—6 of Fig. 5 and Figs. 7, 8, and 9, are views in elevation on the same scale as Fig. 5 illustrating the respective tumblers.

1 represents the lock casing which is made in two half sections, but for convenience of description, I shall refer to one-half section as the body of the casing 1, and the other half section as the front 2. These parts are securely riveted together so as to prevent access to the interior of the casing.

3 is the shackle pivotally secured to the casing at one end by means of a pin 4 and engaged by a spring 5 within the casing to throw the shackle to open position. In the free end of the shackle 3, a recess 6 is pro-

vided to receive a locking bolt 7, the latter guided in a bearing 8 and held in locked position by a coiled spring 9. The bolt 7 and the free end of the shackle 3 are rounded or beveled as clearly shown, so that the shackle when forced into closed position, will displace the bolt and permit the latter to spring into the recess 6 and lock without any manipulation of the tumblers herein-after described.

10, 11, and 12 represent my improved tumblers, each of which is provided with an opening 13 to receive a pivot pin 14, and have rotary or pivotal mounting on the pin. 70 The tumbler 10, which is located adjacent the back wall of casing 1, is provided with a bifurcated finger 15 which is positioned in an annular groove 15 in the locking bolt 7, and operates to withdraw the bolt when the tumbler is given sufficient pivotal movement. This tumbler is held in its normal position by means of the spring 9 on the bolt 7, and the movement of the tumbler overcomes the tension of the spring to withdraw the bolt. 80 The tumbler 11 is located in front of tumbler 10, and is provided at one end with a curved tongue 16. The tumbler 12 is located against the outer face of tumbler 11, and is provided at one end with a curved tongue 85 17. A spring 18 is coiled between its ends around the pivot 14. This spring bears at one end against the tongue 16 of tumbler 11, and at its other end against the tongue 17 of tumbler 12, serving the double function 90 of holding these tumblers in their normal positions.

The tumblers 10, 11, and 12 are moved by four plungers 20, 21, 22, and 23 respectively. These plungers are mounted in openings 24 in the bottom of casing 1, and also in openings 25 in a guide bar 26, the latter secured in the casing adjacent the bottom thereof as clearly shown. These plungers are each provided with coiled springs 27 located around the same between the guide bar 26 and an annular shoulder 28 on the plungers. The springs therefore press the plungers longitudinally in a downward direction, and the shoulders 28 serve as bearing points for the ends of the springs and also limit the outward or downward movement of the plungers by engagement with the bottom of the casing 1. Plungers 20 and 21 are longer than plungers 22 and 23, and at their inner ends are provided with laterally projecting fingers 29 and 30

respectively. Plunger 23 is adapted when moved inwardly or upwardly to engage a lug 31 projecting laterally from one end of tumbler 12. Plunger 22 engages the curved tongue 16 on tumbler 11. Plunger 21, or rather the finger 30 of the plunger 21 is adapted when permitted to engage the lower wall 32 of tumbler 10, but this movement is not sufficient to completely withdraw the bolt. The finger 29 of plunger 20 is adapted when permitted, to engage the wall 33 of tumbler 10, and compel the withdrawal of the bolt, however, the tumblers 11 and 12 are of such a shape that they normally operate as shutters to prevent the turning movement of plungers 20 and 21, and must be moved by the plungers 22 and 23 before plungers 20 and 21 can be turned to operative position, and such operation must be in proper succession. Normally, the parts are in the position shown in Figs. 1 and 5. That is to say, the plunger 23 is located under lug 31, plunger 22 is located under tongue 16, plunger 21 is located beside or in front of tumbler 12, the latter in such position as to prevent the rotary movement of the plunger to position the tongue under the wall 32 of tumbler 10. Plunger 20, at its inner end, is located in front of tumbler 11, the latter preventing turning movement of the plunger to position the finger 29 under the wall 33 of tumbler 10.

To operate the lock, plunger 23 is first moved upwardly as shown in Fig. 2, thereby moving tumbler 12 on its pivot and moving said tumbler out of the way of finger 30. The next operation is to turn the plunger 21 so as to position the finger 30 under the wall 32 of tumbler 10. The next operation is to press the plungers 21 and 22 upwardly, as shown in Fig. 3. The upward movement of plunger 21 by reason of the engagement of finger 30 with wall 32, moves the tumbler 10 on its pivot, but not far enough to entirely withdraw the bolt as shown in Fig. 3. The upward movement of plunger 22, by reason of its engagement with the tongue 16, causes the tumbler 12 to swing on its pivot and move out of the way of finger 29. The next operation is to turn the plunger 20 so as to position the finger 29 under the wall 33 of tumbler 10. The final operation is to press upwardly plunger 20, which moves tumbler 10 to complete the withdrawal of the bolt and release the shackle as shown clearly in Fig. 4. When the plungers 20 and 21 are given a quarter turn to move them out of the path of the tumblers, the spring 18 and the spring 9 return the tumblers to normal position, while the springs 27 return the plungers to normal position, and as soon as the shackle is closed, it will be automatically locked by the spring-pressed bolt 7.

It is to be understood that all of the plungers

are capable of rotary as well as longitudinal movement, and in order to release the lock, it is necessary for the operator to know just how to manipulate and the order of operation of the several plungers. This may be varied so as to change the combination of the lock, and hence the invention is not limited to the precise shape of the tumblers or the precise construction and operation of the plungers, but I consider myself at liberty to make such changes and alterations as fairly fall within the spirit and scope of the appended claims.

Having thus described my invention, what I claim as new and desire to secure by Letters Patent is:

1. A padlock comprising a casing, a shackle pivotally connected at one end to the casing, a spring-pressed bolt in the casing adapted to engage the free end of the shackle, a tumbler in the casing engaging the bolt, and a plunger projecting from the casing, said plunger adapted to be turned and moved longitudinally and having a finger at its inner end to engage the tumbler, substantially as described.

2. A padlock comprising a casing, a shackle pivotally connected at one end to the casing, a spring-pressed bolt in the casing adapted to engage the free end of the shackle, a tumbler in the casing engaging the bolt, a plunger projecting from the casing, said plunger adapted to be turned and moved longitudinally and having a finger at its inner end to engage the tumbler, a second tumbler in the casing normally preventing rotary turning movement of the plunger to position the finger in operative engagement with the first-mentioned tumbler, and a second plunger controlling the movement of the last-mentioned tumbler, substantially as described.

3. A padlock, comprising a casing, a shackle pivotally connected at one end to the casing, a spring-pressed bolt normally engaging the free end of the shackle to hold the same in locked position, a plurality of pivoted tumblers in the casing, one of said tumblers operatively engaging the bolt, a plurality of plungers located in the casing and projecting beyond the casing, said plungers adapted to move longitudinally and also adapted to turn, said plungers constructed to engage the tumblers and control the release of the bolt, substantially as described.

4. A padlock, comprising a casing, a shackle pivotally connected at one end to the casing, a spring-pressed bolt normally engaging the free end of the shackle to hold the same in locked position, a plurality of pivoted tumblers in the casing, one of said tumblers operatively engaging the bolt, a plurality of plungers located in the casing and projecting beyond the casing, said plun-

gers adapted to move longitudinally and also adapted to turn, certain of said plungers having fingers at their inner ends adapted to be positioned under walls of the tumbler engaging the bolt, and the other of said tumblers normally positioned so as to prevent the turning movement of the plungers having the fingers, substantially as described.

- 10 5. A padlock, comprising a casing, a shackle pivotally connected at one end to the casing, a spring-pressed bolt normally engaging the free end of the shackle, a tumbler pivotally supported in the casing and operatively engaging the bolt, a pair of plungers supported in the casing and projecting therefrom, said plungers adapted to move the tumbler in a direction to release the bolt, other tumblers pivotally supported in the casing and normally preventing operative engagement of the plungers with the first-mentioned tumbler, and other plungers mounted in the casing and projecting therefrom and adapted to operate the last-mentioned tumblers, substantially as described.
- 15 6. A padlock, comprising a casing, a shackle pivotally connected at one end to the casing, a spring-pressed bolt normally engaging the free end of the shackle, a tumbler pivotally supported in the casing and operatively engaging the bolt, a pair of plungers supported in the casing and projecting therefrom, said plungers adapted to move the tumbler in a direction to release the bolt, other tumblers pivotally supported in the casing and normally preventing operative engagement of the plungers with the first-mentioned tumbler, and other plungers mounted in the casing and projecting therefrom and adapted to operate the last-mentioned tumblers, substantially as described.
- 20 7. A padlock, comprising a casing, a shackle pivotally connected at one end to the casing, a spring engaging the pivoted end of the shackle and adapted to throw the latter to open position when permitted, a spring-pressed bolt normally engaging the free end of the shackle holding the same in locked position, a plurality of pivoted tumblers in the casing, one of said tumblers having a bifurcated finger operatively engaging in a groove in the bolt, a plunger for moving the tumbler having a finger thereon, the other of said tumblers normally preventing operation of the plunger, and other plungers controlling the operation of the last-mentioned tumblers, substantially as described.
- 25

in the casing and normally preventing operative engagement of the plungers with the first-mentioned tumbler, and other plungers mounted in the casing and projecting therefrom and adapted to operate the last-mentioned tumblers, a single spring holding the last-mentioned tumblers in normal position, and springs on the respective plungers holding them in normal position, substantially as described.

40 8. A padlock, comprising a casing, a shackle pivotally connected at one end to the casing, a spring engaging the pivoted end of the shackle and adapted to throw the latter to open position when permitted, a spring-pressed bolt normally engaging the free end of the shackle holding the same in locked position, a plurality of pivoted tumblers in the casing, one of said tumblers having a bifurcated finger operatively engaging in a groove in the bolt, a plunger for moving the tumbler having a finger thereon, the other of said tumblers normally preventing operation of the plunger, and other plungers controlling the operation of the last-mentioned tumblers, substantially as described.
